CLAIM

The ornamental design for an edible ice cream cornet, as shown and described.

DESCRIPTION

The patent or application file contains at least one drawing executed in color. Copies of this patent or patent application publication with color drawing(s) will be provided by the Office upon request and payment of the necessary fee.

FIG. 1 is a side perspective view of an exemplary edible ice cream cornet of the present invention.

FIG. 2 is a side perspective view of another exemplary edible ice cream cornet of the present invention.

FIG. 3 is a side perspective view of another exemplary edible ice cream cornet of the present invention; and,

FIG. 4 is a side perspective view of another exemplary edible ice cream cornet of the present invention.

**1 Claim, 4 Drawing Sheets
